Primary Examiner — Cynthia Ramirez*(74) Attorney, Agent, or Firm* — Chernoff Vilhauer LLP(57) **CLAIM**

The ornamental design for a cart with an adjustable top, as shown and described.

DESCRIPTION

FIG. 1 is a top, left, front isometric view of a cart with an adjustable top showing my new design;
FIG. 2 is a front side elevational view of the cart shown in FIG. 1;

FIG. 3 is a left side elevational view thereof;

FIG. 4 is a right side elevational view thereof;

FIG. 5 is a top plan view thereof;

FIG. 6 is a back side elevational view thereof; and,

FIG. 7 is a top, left, front isometric view thereof, showing the top of the cart in an alternate position.

The broken line showing of shelves in the figures included for the purpose of illustrating environment and forms no part of the claimed design.
